Primary Examiner — Jack Reickel*Assistant Examiner* — Bobby W Jones, II(74) *Attorney, Agent, or Firm* — Rosenberg, Klein & Lee(57) **CLAIM**

The ornamental design for a hydrogen generator, as shown and described.

DESCRIPTION

FIG. 1 is a perspective view of a hydrogen generator according to the invention;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof, and,

FIG. 8 is a bottom view thereof.

All the broken lines in the figures are directed to environment and are for illustrative purpose only. The broken lines form no part of the claimed design.

1 Claim, 8 Drawing Sheets(56)
